UNITED STATES PATENT OFFICE.

GEORGE L. PIERCE, OF BROOKLYN, NEW YORK, ASSIGNOR TO A. G. SPALDING & BROS.,
OF NEW YORK, N. Y., A CORPORATION OF NEW JERSEY.

SHOE.

1,184,013.

Specification of Letters Patent.

Patented May 23, 1916.

Application filed April 15, 1914. Serial No. 831,908.

To all whom it may concern:

Be it known that I, GEORGE L. PIERCE, a citizen of the United States of America, and resident of Brooklyn, in the county of 5 Kings and State of New York, (whose post-office address is 660 Pacific street, Brooklyn, New York,) have invented certain new and useful Improvements in Shoes, of which the following is a specification.

10 This invention is designed to provide an improved type of foot-covering, and especially aims to provide a boot or shoe constructed to subserve in a high degree the purposes of comfort, security, protection 15 and durability, during athletic exercises of the wearer, as for instance in the game of hockey.

An important object of the invention is 20 to provide a boot or shoe of the above nature adapted particularly to protect the instep of the wearer from danger of injury due to accidental or other blows of hockey sticks or other objects which are sometimes brought with force against the foot of a 25 testant.

Other objects and aims of the invention, more or less broad than those stated above, together with the advantages inherent, will 30 be in part obvious and in part specifically referred to in the course of the following description of the elements, combinations, arrangements of parts, and applications of principles constituting the invention; and the scope of protection contemplated will 35 appear from the claims.

40 Referring now to the accompanying drawing, which is to be taken as a part of this specification and wherein is shown one of the various possible embodiments of this invention as at present preferred: Figure 1 is a view in side elevation, showing said embodiment; Fig. 2 is a top plan view of the parts shown in Fig. 1; and Fig. 3 is a perspective view of an illustrative type of protector which could be used in connection 45 with the shoe proper illustrated in Figs. 1 and 2.

Examining the drawing, there is shown an illustrative supporting shoe structure of

a well-known type, including a sole 4, a 50 vamp 5, quarters 6, a plurality of lacing-holes 7, a toe-cap 8, and a lacing 9 and the usual tongue inside the shoe behind the lacing 9. In Fig. 1 the toe-cap 8 is shown as being integrally formed with a tongue-like, 55 upwardly and rearwardly extending member 10 as shown, although it is of course obvious that this member 10 or an equivalent thereof could otherwise be carried by or attachable to the shoe as, for instance, by 60 the stitching 10' disclosed in Fig. 2, or by lacing along this line 10'. The member 10 as disclosed in Figs. 1 and 2, it will be observed, is generally of an oblong outline, and is preferably apertured as at 11 (Fig. 65 2). Suitably attached to the rear face of said member 10 is a preferably resilient shock-absorbing cushion 12, which may be of felt or the like. This cushion 12 has a plurality of apertures, certain of which 70 register with certain or all of the apertures 11.

In connection with the member 10 disclosed in Figs. 1 and 2, there is in the present instance associated a part 13, which 75 may hereinafter be referred to as the instep-hood. This instep-hood is disclosed as being generally of a cruciform outline, consisting of a main portion (which may or may not be apertured), oppositely off-set from 80 which are two strap-like extensions 13'. One of these extensions is preferably terminally anchored by suitable stitching or otherwise at one side of the shoe structure, and the other end may have a series of 85 spaced buckle-engaging holes 15. A buckle 15', carried by strap 16, said strap being preferably terminally anchored within the shoe structure as adjacent the location 18, is adapted to coöperate with one of the extensions 13' and with one of the holes 15 formed in the latter, as disclosed in Figs. 1 and 2, whereby to cause or coöperate in causing the member 10 and its cushion 12 to be brought into yielding engagement and 90 conformity with the foot of the wearer. Of course it is understood that each extension 95 13' and even the lower or forward portion of

member 10, could terminally or otherwise carry a buckle similar to the buckle 15' or an equivalent means for the temporary attachment of either or all of said parts to the 5 shoe structure; there being provided in connection therewith, of course, a suitable plurality of coöperating straps or the like which would preferably be terminally anchored to the shoe structure.

10 Having thus described the construction of this embodiment of my invention, a preferable method of mounting the same upon the foot of the wearer may next be indicated. With the laces 9 suitably loosened, 15 the foot is inserted into the interior of the shoe; and the interior tongue 4 is next adjusted. The laces are then passed through the lacing-holes 7 and adjusted to bring the vamp 5' firmly against the foot, the laces being 20 then permitted to dangle until the next-described step is completed, to wit, the adjustment of the member 10, plate 12 and instep-hood 13. Assuming the shoe to have been constructed in accordance with the 25 closure of Figs. 1 and 2, that is, with the lower forward terminus of member 10 and with one of the extensions 13' terminally anchored to the shoe structure, the buckle 15' carried by the strap 16 is caused to coöperate 30 with one of the holes 14 formed in the free extension 13', to draw and maintain the cushion 12 snugly against the instep. The laces 9 are then passed upwardly as shown through a plurality of the apertures in cushion 12, and through the registering apertures 11 in the member 10, and tied or 35 knotted in place, as indicated at 11', to aid in supporting the integrity of the entire structure.

40 In Fig. 3 a further modification of the structure of Figs. 1 and 2 is illustrated. Here a cushion 12 similar to the cushion above considered is present. Associated with the cushion and suitably attached 5 thereto is a unitary member 18'', of a generally cruciform outline, and adapted to be substituted for the member 10 and the instep-hood 13 shown in Figs. 1 and 2. It will be seen that member 18'' is provided 50 with two oppositely off-set extensions 18'. These extensions 18' could of course be so constructed that one of them would be similar to one of the extensions 13' and the other would be similar to the other extension 13'. 55 But as illustrated in Fig. 3 each of said extensions 18' is provided with a plurality of buckle-engaging holes 19. The extensions 18' as illustrated could of course be used in connection with a plurality of straps and 60 buckles on opposite sides of the shoe and respectively similar to the strap 16 and the buckle 15' shown in Figs. 1 and 2, thus rendering both the extensions 18' readily detachable from direct connection with the

shoe structure proper. Were the parts 65 shown in Fig. 3, instead of the cushion 12 and the instep-hood 13, suitably associated with the shoe structure illustrated in Figs. 1 and 3, a preferable method of adjusting such a shoe upon the foot of the wearer would be 70 substantially similar to that above described.

It will be seen that the present embodiment of this invention may be worn with the utmost comfort, the cushion 12 by its resilient nature giving a pleasant sense of 75 freedom to the wearer and yet, being held fast by means of the buckle 15' and the laces 9, imparting a feeling of ease and security. The protection afforded the delicate metatarsal bones and sensitive ligaments and 80 nerves associated therewith is certain. Moreover, the foot when incased in the shoe is neat in appearance and the latter not noticeably larger than ordinary.

Inasmuch as many changes could be made 85 in the above construction, and many apparently widely different embodiments of my invention could be made without departing from the scope thereof, it is intended that all matter contained in the above description 90 or shown in the accompanying drawing shall be interpreted as illustrative and not in a limiting sense. It is also to be understood that the language used in the following claims is intended to cover all the generic and specific features of the invention herein described and all statements of the scope of the invention which, as a matter of language, might be said to fall therebetween.

I claim:

1. In a device of the class described, in combination, a shoe structure having opposed flexible portions at the front arranged to overlie a portion of the instep, a cushion arranged to overlie both of said flexible portions, and an instep-hood adjustable upon the shoe structure to direct said cushion against the instep, said hood having a plurality of off-set side extensions arranged to be anchored to the shoe structure. 100

2. In a device of the class described, in combination, a shoe structure having opposed flexible portions at the front arranged to overlie a portion of the instep, a cushion arranged to overlie both of said flexible portions, and an instep-hood adjustable upon the shoe structure to direct said cushion against the instep. 105

3. In a device of the class described, in combination, a shoe structure having opposed flexible portions at the front arranged to overlie a portion of the instep, and a cushion arranged to overlie both of said flexible portions, said cushion being apertured. 110

4. In a device of the class described, in combination, a shoe structure having opposed flexible portions at the front arranged to overlie a portion of the instep; lacing 115

means carried by said flexible portions, a
cushion arranged to overlie said lacing
means, and an aperture formed in said cush-
ion whereby said lacing means may coöp-
5 erate with said aperture to anchor in posi-
tion said cushion.

In witness whereof I have hereunto signed
my name in the presence of two witnesses.

GEORGE L. PIERCE.

In the presence of—

HELEN V. FITZPATRICK,
MARY H. LEWIS.
